UNITED STATES PATENT OFFICE

2,393,830

ELECTRODE HOLDER

Albert H. Smith, South Gate, Calif.

Application January 31, 1944, Serial No. 520,447

2 Claims. (Cl. 219—8)

My invention relates to electrode holders of the general character shown in my Patent No. 2,150,464, issued March 14, 1939. However, an important object of the present construction is to provide an electrode holder of simpler construction.

Another object is to provide an electrode holder that will firmly maintain an electrode in any of a variety of angles during welding.

A further object is to provide in an electrode holder a quickly replaceable tip for holding electrodes.

My invention also has for its objects to provide such means that are positive in operation, convenient in use, easily and quickly operated, economical of manufacture, relatively simple, and of general superiority and serviceability.

The invention also comprises novel details of construction and novel combinations and arrangements of parts, which will more fully appear in the course of the following description. However, the drawing merely shows and the following description merely describes embodiments of the present invention, which are given by way of illustration or example only.

In the drawing, like reference characters designate similar parts in the several views.

Fig. 1 is a longitudinal section of an electrode holder, partly in elevation, embodying the foregoing objects.

Fig. 2 is an enlarged side elevation of the tip of the holder, looking in the direction of the arrow A of Fig. 1.

Fig. 3 is a transverse section taken on the line 3—3 of Fig. 1.

Fig. 4 is a broken, longitudinal section taken at 90° from Fig. 1.

Fig. 5 is a broken elevation, showing a modified construction.

Referring more in detail to the drawing, the reference numeral 6 indicates a tubular, insulating handle for my present electrode holder. A cylindrical conductive bushing 7 is arranged within the handle 6. A binding post 8 at the end of the bushing 7 provides suitable means for connecting with a wire 9 insulated as shown at 10. A plate 12 is disposed to clamp the end of the wire 9 to the bushing 7, and a nut 13 on the binding post 8 in turn clamps the plate in said position.

A pin 14 spans the space within the cylindrical bushing 7. A fibre or other non-conductive disc 15 rests against the pin 14, while a second fibre, insulating disc 16 is disposed opposite the disc 15 with a coil spring 17 arranged between, and abut-

ting, the discs 15 and 16. An insulating sleeve 18 within the bushing 7 envelopes the spring 17.

The head 19 of the binding post 8 spaces the bushing 7 from the insulating handle 6 at one end, and an integral collar 20 on a bolt 21 spaces the other end of the bushing 7 from the handle 6. The head 22 of the bolt 21 is accessible from the exterior through an opening 23 in the handle 6. The head 22 is of reduced diameter, relative to the collar 20. The bolt 21 is screwed into the bushing 7 to hold same in place.

The bushing 7 has a slot 24 in which reciprocates a cross-head 25. The cross-head is connected with a rod 26 by arms 27 arranged around a lever 28 fulcrumed at 29. A grip 30 is fitted on an outer, angular end 31 of the lever 28.

The rod 26 reciprocates in an elongated shell 32. The cylindrical shell 32 is notched laterally, as perhaps best shown in Fig. 2. The notches 33 are in a stepped arrangement, with the upper notch as shown at 33 and the lower notch as suggested at 34. It is to be understood that there are two notches 33 on opposite sides of the shell 32, and that there are two notches 34, one directly opposite the other, in the sides of the shell 32. A welding rod 35 may rest in the upper notches 33 or in the lower notches 34 (as shown in full lines in Figs. 1 and 2), or in one upper notch and one lower notch (as shown in broken lines in Fig. 1). The notches 33 and 34 are overhung by points 36 and 37 respectively, to maintain the rod in the notches. The reciprocating rod 26 is preferably pointed, as shown at 38, to hold the welding rod 35 in the desired notches. The variety of positions of the welding rod 35 makes it convenient to reach different locations of work.

In the form shown in Fig. 5, any suitable handle (not shown) may be attached to the rod 39. A cap 40 is screwed upon a threaded end 41 of the rod 39. The rod 39 is pointed as suggested at 42. It is believed clear without further illustration that the cap 40 is hollow and contains upper and lower notches, as shown and described in the hereinabove construction. A welding rod 43 is shown in the lower notches of the cap 40.

In the operation of my preferred constructions (shown in Figs. 1 to 4 inclusive), the point 38 of the rod 26 is drawn rearward by depressing the grip 30 to the broken line position in Fig. 1. This movement of the grip 30 is communicated to the rod 26 by the lever 28 bearing upon the inclined or cam face 44 of the cross-head 25.

Rearward movement (to the right in Fig. 1)

of the cross-head 25 is resisted by the spring 17 behind the disc 16, so that when the grip 26 is released, the spring 17 urges the grip 26 back to the full line position in Fig. 1 and pushes the rod 28 to the position shown in that figure. It is believed clear that the cross-head 25 reciprocates in the slot 24 of the bushing 1 and that the lever 28 is mounted to swing in a slot 45 in the handle 8. The inner end of the shell 32 acts as a stop for the lever 28, as also shown in Fig. 1. The variety of positions of the welding rod 38, as shown in full and broken lines in Fig. 1, is believed clear from the foregoing.

In the use of the modified form shown in Fig. 5, the screw cap 40 is partially unscrewed from the threaded end 41 of the rod 38. This unscrewing movement releases the welding rod 43 from the point 42. When the welding rod 43 is readjusted or replaced, the cap 40 is again screwed home until the point 42 maintains the welding rod 43 in position in the notches of the cap 40.

While I have illustrated and described what I now regard as the preferred embodiments of my invention, the constructions are, of course, subject to modifications without departing from the spirit and scope of my invention. I, therefore, do not wish to restrict myself to the particular

forms of construction illustrated and described, but desire to avail myself of all modifications that may fall within the scope of the appended claims.

Having thus described my invention, what I claim and desire to secure by Letters Patent is:

1. In an electrode holder, an elongated tubular shell having near the outer end thereof, a series of crotches for seating a welding rod, said crotches defined by opposed edges of the shell disposed at an angle to the vertical and opposed edges parallel with the axis of said shell, a spring-urged rod mounted for movement in the shell to hold a welding rod in the crotches thereof, and lever means connected to draw the rod away from the crotches against the action of the spring.

2. In an electrode holder, a hollow shell closed at one end and having near such closed end a peripheral cut-out forming opposed, rearwardly inclining edges and opposed edges parallel with the axis of said shell, said edges defining stepped crotches for a welding rod, a plunger rod movable in said shell in one direction by a spring to press the welding rod in the crotch thereof and manually in another direction to release said welding rod.

ALBERT H. SMITH.
